UNITED STATES PATENT OFFICE.

JOSEPH J. STEHLING, OF MILWAUKEE, WISCONSIN.

LEACH-CASTING MACHINE.

No. 921,021.

Specification of Letters Patent.

Patented May 11, 1909.

Application filed September 4, 1906. Serial No. 333,073.

To all whom it may concern:

Be it known that I, JOSEPH J. STEHLING, of Milwaukee, Wisconsin, have invented a Leach-Casting Machine, of which the following is a specification.

The object of the present invention is to provide an improved form of machine for removing leached or spent tan-bark from the leaching vat used in extracting the tanning solution in the process of making leather. The extraction process is carried on in large cylindrical vats or tanks by steeping therein a quantity of the tan-bark in hot water, and the said tanks are provided with a false bottom, whereby the infusion may be drawn off when the process has proceeded far enough, leaving the bark behind on said false bottom. A hole is provided through both bottoms of the tanks, through which the bark is thrown out in emptying it; the said hole being stopped by a hollow plug during the infusion process.

Certain machines for removing the spent tan bark have been heretofore invented, these machines comprising in principle a shaft having radial arms provided with shovels or scoops and said shaft being caused to rotate in the tank, whereby the bark is gathered up and discharged from the aforesaid opening in the bottom.

The object of the present invention is to improve on machinery of this type by overcoming certain objections thereto and at the same time providing a single machine which shall be applicable to a plurality of vats and can be readily removed from one to another as may be desired.

In my new apparatus, the entire machine including the rotary shaft and driving mechanism is mounted on tram-rails and adapted to be rolled along from one vat to another, the aforesaid shaft and pitching arms being arranged to be raised and lowered from and into the infusion vats.

The invention consists of the novel combinations and constructions which will be hereinafter more fully described, and particularly set forth in the claims.

For the purpose of illustrating my invention and its mode of operation, I have illustrated the same in the accompanying drawings, wherein—

Figure 1 is a longitudinal section through a leaching-vat and the leach-casting machine operating therein. The said vat is supposed to be one of a series, as ordinarily

used in tanneries; Fig. 2 is a side elevation of the machine, the cross-head and arms being, however, broken away; Fig. 3 is a plan view of the same; Fig. 4 is an end view 60 of the same from the right of Fig. 1; Fig. 5 is a horizontal section of one side of the tank and one end of the cross-beam, to show the manner of guiding the latter in the vat; Fig. 6 is a vertical medium section, and Fig. 65 7 a plan of the collar-bearing supporting the cross-head; Fig. 8 is an end view of the cross-beam; Fig. 9 is a longitudinal section on the line 9 of Fig. 8; and Fig. 10 is a fragmentary longitudinal section and Fig. 11 a 70 transverse section through the shaft to illustrate the telescoping joint.

In these drawings every reference letter and numeral refers always to the same part.

Fig. 1 shows a cylindrical vat or tank 21 having a bottom 22, and a short distance therefrom a false bottom 23, through slits or perforations in which the tan liquor can run when it is being drawn from the vat, leaving the spent bark behind in the vat. At one 80 side is an opening 24 from which the spent bark is pitched to remove it from the tank after the leaching process. This opening is closed during the steeping by a plug extending upwardly above the level of the bark. 85 The top of the vat is closed by a cover 25 having a longitudinal opening in the center through which the leach-casting devices descend. As so far described, the vat is of an ordinary construction and constitutes no 90 part of my invention. This vat is supposed to be one of a row of vats over which pass a pair of parallel beams 26 secured together in proper relation at intervals, as by ties 27 and carrying tram-rails 28 on which travels a 95 frame or carriage 29 with wheels 30 and 31 rolling on said rails; the wheels 31 on one side being flanged, as shown, to guide the carriage on the rails.

The carriage 29 has mounted thereon in 100 the center a bearing 32 for a telescoping shaft made in two or more sections 33, 34; the upper section 33 being journaled in the bearing 32 as shown, and provided with a keyway 35 along its entire length. On the upper side of 105 the bearing 32 turns a bevel-gear 36, which is provided with a key 37 engaging the keyway 35 of the shaft; said shaft sliding freely in the bearing and gear, but being nonrotatable relative to the latter by reason of said 110 keyed engagement. The section 33 of the shaft is provided with a cross-pin or cotter

38 which prevents such section from falling through the nave of the wheel. The said upper shaft-section 33 is tubular and provided at its lower end with an internal collar 5 or flange 39 while the lower section 34 is of the proper diameter to fit said internal collar 39 and is provided with a head 40 which fits the interior diameter of the shaft-section 33. The shaft-section 34 is in turn provided 10 with a keyway 41 along its entire length and there is a key 42 secured to the collar 39 and engaging in said keyway whereby to prevent rotation of the section 34 relative to the section 33 but permitting longitudinal movement. 15

The lower section 34 of the shaft carries fixed in rigid relation thereto a crosshead 43 which has sockets receiving a pair of radial arms 44 having a sweep as nearly as possible 20 equal to the interior diameter of the vat. These arms are made of ordinary gas-pipe and are secured in their sockets by set-screws 45 and they carry a plurality of shovels or scoops 46 which are obliquely connected in a 25 manner to turn over the bark and pitch it toward the outlet aperture 24. The underside of the crosshead 43 also has scoops 47 fixed thereto for a like purpose, and at the point on each of the arms 44 which comes 30 immediately over the opening 24 there is a plow 48 which has secured to its rear side a plurality of vertical spring-wires 49 and a pair of horizontal spring wires 50, these latter acting to scrape the sides of the vat and 35 detach therefrom any adhering bark.

The crosshead 43 is provided with an integral collar-bearing 51, which is clearly illustrated in Fig. 6. This bearing is supported in bearing-blocks 52, which are mounted on 40 a cross-beam 53 extending from side to side of the vat, and having each of its ends guided between a pair of guide strips 54 (see Fig. 5). The ends of this cross-beam are formed, as shown in Figs. 8 and 9, with a pair of vertical 45 angle-bars 55 sliding on the edges of the guide-pieces 54 and having their lower edges sharpened whereby to remove any adhering bark from the guides as the cross-beam descends; and to remove the bark from the 50 space between the guides an oblique plate 56 is fixed to the under side of the end of the cross beam and sharpened on its lower edge as shown; this plate abutting on the wall of the vat between said guides. The cross- 55 beam 53 is made up of a pair of channel-beams 57 secured together at the ends by transverse channel-pieces 58 to which are secured the vertical angle-bars 55 and the beams 57 are secured together in the center 60 by the bolts 59 which hold the bearing blocks 52 in place. The crosshead, arms and shovels are therefore swung in a pivotal manner from the cross-beam 53, and this beam is lowered into and raised from the vats by means of a pair 65 of ropes or like flexible connections 60, which

are wound upon a pair of drums 61 mounted on a shaft 62 near one end of the carriage; the rope at the opposite side of the shaft being caused to pass over a sheave 63, which turns loosely on a fixed shaft 64 mounted in 70 pedestals 65 and secured thereto by set screws 66; said sheave 63 moving longitudinally on said shaft to keep in alignment with the rope as it winds or unwinds from the drum 61. 75

The shaft 62 turns in bearings 67 and carries a worm-wheel 68, which is keyed thereto as are also the drums 61, and is driven to wind or unwind the rope upon said drums by a worm 69 mounted on a longitudinal shaft 80 70 turning in bearings 71. Said shaft has on one end thereof a spur-gear 72 which is engaged by one or more projecting lugs 73 on the periphery of the wheel 36; and the gear 72 is keyed to the shaft 70 by a spline 74, 85 which permits said wheel to be slid back out of the way of the lug or lugs 73. At its opposite end the shaft may be provided with a removable crank, 75, to permit the ropes 60 to be wound up by hand when desirable. 90

The driving mechanism of the machine comprises a sprocket-wheel 76, forming part of a clutch-drum 77, which rotates loosely on a longitudinal shaft 78, the latter being mounted in bearing posts 79, and having 95 keyed on one end thereof a bevel-pinion 80 which meshes with the bevel gear-wheel 36 and drives the latter. The clutch-drum 77 is clutched to the shaft 78 by the co-operating part of the clutch, which is of any desirable 100 type and forms no part of my present invention, the clutch-mechanism being entirely located within the drum 77 and not appearing separately in the drawings. A projecting dog 82 is shown, which is engaged by 105 a sliding clutch-cone 83, the latter being operated by a hand-lever 84 pivoted at 85 and connected with the cone in any usual manner to slide it longitudinally on the shaft and thus turn the dog 82 and cause the 110 clutch to lock whereby the shaft 78 is driven from the sprocket-wheel 76. It will be understood that the sprocket-wheel 76 is itself driven from an overhead shaft or other 115 source of power, to which it is connected by a driving-chain this chain being removed whenever the carriage is moved from one vat to another. I do not, however, consider this mode of driving essential to my invention, as I may in some cases have the driving 120 motor mounted directly on the carriage.

At one side of the carriage is mounted a countershaft 86 which rotates in bearings 87, and has mounted on one end gear 88, which is splined to and slidable thereon for a 125 short distance, so as to engage or disengage with a spur-gear 89 formed on the periphery of the drum 77. A longitudinal movement of the gear 88 is effected by means of a yoked hand-lever, 90 pivoted on a bracket 91 to the 130

carriage-frame and operatively connected with a collar 92 on the hub of the gear 88.

On its opposite end the shaft 86 carries a spur-gear 93, which is in position to mesh 5 with the wheel 72 when the latter is thrown back out of the path of the lug 73, as shown by the dotted line position in Fig. 3.

The operation of my machine is as follows: The carriage being rolled into position over 10 the vat from which the bark is to be removed, the wheel 76 is connected by a chain with the source of power as already described. By means of the crank 75 the cross-beam 53 is now lowered with the pitching-arms and 15 shovels into the tank the proper distance, until the shovels reach the bark. The wheel 88 being in the position shown in the drawings, the power is now turned on by throwing the clutch lever 84 to the left. The wheel 36 20 now begins to turn, rotating the pitching-arms and shovels which scrape up the bark and pitch it out of the hole 24, and at every revolution of the shaft the wheel 72 is turned one tooth or as much as may be desirable, 25 according to the number of lugs 73, thus lowering the arms coincidently with the pitching-operation. After the bark is all removed, to raise the pitching-arms the clutch 77 is thrown out of action so as to 30 cease turning the arms, and the wheel 88 being thrown into gear with the wheel 89, and the wheel 72 into gear with the wheel 93, the wheel 72 is now turned rapidly in the reverse direction so as to wind the ropes 60 on the 35 drums, and this continues until the cross-beam 53 and arms 44 are completely raised out of the vat into the position shown in Fig. 2, whereupon the power is thrown off.

The object of making the shaft in two sections is to prevent the same from extending 40 so high when raised as to strike the roof or floor above and it will be obvious that instead of making the shaft in two sections it may be made in three or more sections if 45 desired, each one within the other in the same manner as already described.

While I have hereinabove described the preferred form of my invention, I wish it understood that I do not limit myself to 50 any one of the particular features thereof, and I fully realize that it is capable of numerous modifications without departing from the principle thereof, and I consider such modifications and omissions may be 55 made without departing from the principle of my invention. Further, I realize that my machine is applicable to other manufacturing processes than leather-making, and do not confine myself merely to its use 60 in the extraction of a tanning solution.

Having thus described my invention, what I claim as new and desire to secure by Letters Patent, is:

1. In a leach casting machine the combination of a carriage, winding drums station-

arily mounted thereon, a cross beam suspended from said carriage by flexible connections passing over said drums, a rotary pitching device journaled in said beam, driving mechanism mounted on said carriage, 70 and a rotating connection between said mechanism and said pitching device, said beam and pitching device being permanently connected with the carriage and portable therewith, substantially as described. 75

2. In a leach casting machine the combination of a carriage, winding drums stationarily mounted thereon, a cross beam suspended from said carriage by flexible connections passing over said drums, a rotary 80 pitching device journaled in said beam, a horizontal driving wheel mounted on said carriage, and a shaft attached at its lower end to said pitching device and having a splined connection with said wheel, substantially as described. 85

3. The combination with a leaching vat having vertical guides at opposite sides thereof and a track passing transversely over said vat, of a carriage mounted on said track, winding drums stationarily mounted on said carriage, a cross beam adapted to engage at the ends with said guides and suspended from said carriage by flexible connections passing over said drums, a rotary pitching device centrally journaled in said beam, and driving means mounted on said carriage and having an extensible rotating connection with said pitching device, substantially as 90 described. 95

4. The combination with a leaching vat having vertical guides at opposite sides thereof, and a track arranged transversely over said vat, of a carriage mounted on said track, winding drums stationarily mounted 100 on said carriage, a cross beam adapted to engage at the ends with said guides and suspended from said carriage by flexible connections passing over said drums, a rotary pitching device centrally journaled in said beam, a driving mechanism mounted on said carriage, and a telescoping shaft connecting 105 said driving mechanism with said pitching device, substantially as described. 110

5. In a leach casting machine the combination with a frame of a horizontal driving gear mounted on said frame and having a peripheral tooth or lug, a vertically movable rotary pitching device having a self adjusting 115 rotating connection with said gear, winding drums stationarily mounted on said frame and provided with a worm gear, flexible connections attached to said pitching device and to said drums, and a shaft having a worm engaging said worm gear and a gear in the 120 path of the peripheral tooth or lug on the driving gear, substantially as described. 125

6. In a leach casting machine the combination of a carriage, a horizontal gear mounted thereon and provided with a peripheral tooth 130

or lug, means for rotating said gear, winding drums stationarily mounted on said carriage and provided with a worm gear, a vertically movable rotary pitching device suspended 5 from said carriage by flexible connections attached to said drums, a telescoping shaft connecting said pitching device with said driving gear, and a shaft provided with a worm in mesh with said worm gear and a gear 10 in the path of the peripheral tooth or lug on the driving gear, substantially as described.

7. The combination with a leaching vat having vertical guides at opposite sides thereof and a track passing over the vat, of a carriage 15 mounted on said track, a horizontal driving gear mounted on said carriage and provided with a tooth or lug, means for turning said gear, winding drums stationarily mounted on said carriage and provided with a worm gear, 20 a crank shaft having a worm meshing with said worm gear, and a gear movable into and out of the path of the tooth or lug on the driving gear, a vertically movable cross beam adapted to engage at its ends with said guides 25 and suspended from said carriage by flexible connections attached to said drums, and a rotary pitching device centrally journaled in said beam and connected with said driving gear by a telescoping shaft, substantially as 30 described.

8. The combination with a leaching vat having vertical guides at opposite sides thereof and a track passing over the vat, of a carriage mounted on said track, a horizontal 35 gear mounted on said carriage and provided with a tooth or lug, a driving shaft for turn-

ing said gear, winding drums stationarily mounted on said carriage and provided with a worm gear, a crank shaft having a worm meshing with said worm gear, and a gear 40 movable into and out of range with said tooth or lug, a counter shaft provided with gears for connecting it with the gear on the crank shaft and a gear on the driving shaft, a cross beam fitted to engage at the ends with 45 said guides and suspended from said carriage by flexible connections attached to said drums, and a rotary pitching device centrally journaled in said beam and connected with said horizontal gear by a telescoping shaft, 50 substantially as described.

9. The combination with a leaching vat having vertical guides at opposite sides thereof, of a frame arranged over said vat, a vertically movable cross beam adapted to 55 engage at the ends with said guides and provided with scrapers extending below the ends of the beam close to the guides for removing material adhering thereto, means for suspending said beam from said frame and for lowering and raising the same into and out of the vat, a rotary pitching device centrally journaled in said beam, and means for rotating said pitching device while it is being lowered 60 into the vat, substantially as described. 65

In testimony whereof I have hereunto signed my name in the presence of two witnesses.

JOSEPH J. STEHLING.
